STEAM PRESSING IRON

Morris A. Schwartz, Los Angeles, Calif.

Application May 21, 1941, Serial No. 394,399

11 Claims.

(Cl. 38—77)

My invention relates to a steam pressing iron of the type in which a steam generator is provided in the iron and water is supplied in regulated quantities to the generator and transformed to steam by heat supplied from the iron. Usually such heat is provided through the medium of one or more electric heating units which also heat the ironing sole of the iron so that in the progress of the ironing steam is discharged through the ironing sole to the fabrics or other fabrics being worked by the iron.

In this type of iron having its self contained steam generator, it is desirable to assemble the various unitary parts of the generator by riveting and in this difficulty has been experienced to secure water and steam tight joints. A steam generator of this type must be made quite thin in order that heat may be transferred by conduction or otherwise through the generator from a heating unit thereabove, transform the water into the steam and supply heat to the sole plate.

One of the objects and features of my invention is constructing an assembled steam generator of a riveted type by employing two plates with grooves or openings therebetween for the flow of water and the generation and flow of steam, then providing a cement and a cover plate fitted adjacent one of the plates having the passages therebetween. The whole assemblage is then riveted together. Considered more specifically as to the steam generator, this provides a bottom plate with channels formed in its upper surface for the passage of water, the generation of steam and the flow of steam to outlet perforations through the bottom plate. This bottom plate is characterized by curved surfaces adjacent the rivet holes on its upper side. A cap plate of thin material such as a thin copper sheet fits on the bottom plate which is usually aluminum, a layer of cement ceramic is then spread on the cap plate and to confine this cement I provide a top plate of good heat conducting material such as sheet aluminum, this also having complementary rivet openings. The assembly of the plates with the mastic is then tightly riveted, the riveting causing the cap plate to conform to the curved upper edges of the bottom plate adjacent the rivet perforations. This construction therefore provides a thin flat steam generator which may be shaped to conform to the ironing shoe with which it is to be used. The shoe itself would then have steam outlets or perforations aligning with those of the bottom plate. In this type of construction another feature of my invention is forming the bottom plate with an in-

tegral hollow water duct structure which may connect to a reservoir carried by the iron or by a flexible tube to an overhead water supply.

In pressing irons having a self containing steam generator supplied by water from a reservoir carried by the iron, it is necessary to use a check valve or the equivalent to prevent the steam from blowing the water back into the reservoir. Steam is frequently developed with greater rapidity than it can find an outlet through the perforations in the ironing surface of the shoe. The ordinary check valve is not suitable for this as the pressure in the generator must be reduced sufficiently to allow more water to enter through the check valve from the reservoir and until this occurs there is no pressure to drive the water trapped between the check valve and the steam space into such latter space to be turned into steam.

20 My invention therefore comprehends an expandable resilient acting pressure chamber for the water on the discharge side of the check valve so that when the steam pressure causes a back flow of the water and builds up a pressure, the first action is to close the check valve and the water flow from the reservoir and then to cause the trapped water to expand the resilient water chamber, therefore when the steam pressure decreases and before the check valve opens 25 for a further supply from the reservoir, the resiliency of the expansion chamber drives the water into the steam transfer portion of the generator. This maintains a much steadier flow 30 of water and steam than in the conventional simple check valve control.

35 My invention is illustrated in connection with the accompanying drawings, in which:

Fig. 1 is a side elevation of the iron taken in the direction of the arrow 1 of Fig. 2.

40 Fig. 2 is a plan taken in the direction of the arrow 2 of Fig. 1 with the top of the reservoir broken away.

45 Fig. 3 is a vertical transverse section on the line 3—3 of Fig. 1 in the direction of the arrow on a much larger scale.

Fig. 4 is a plan of the steam generator fitted in the sole plate with part of the generator broken away.

50 Fig. 5 is a section through the outlet of the reservoir illustrating the resilient expansion chamber for trapped water.

Fig. 6 is an end elevation of a modification of the iron, the water feed being from an overhead supply.

55 The iron as illustrated in Figs. 1 through 5 is

built up with a sole plate 11, this being illustrated as having the ironing surface 12, an upwardly extending flange 13 which is beveled on the outside but at right angles to the bottom surface on the inside. This sole plate has a top surface 14 usually parallel to the bottom surface, there being a series of steam ducts 15 formed by small preferably drilled holes between the top and the ironing surface. These are usually positioned near the forward end, that is, the point of the iron to give the desired distribution and spread of the steam. The flange 13 at the back of the iron has a notch 16 to accommodate the water feed duct to the steam generator hereunder described. There are also drilled and tapped inclined screw sockets 17 in the rim which are spaced at the desired intervals for clamping the steam generator and the heating assemblies in place fitting within the flanges of the sole plate. This sole plate has been shown as of the conventional shape. It will be appreciated that it may however be made in any desired configuration.

The steam generator assembly 25 is indicated particularly in Figs. 3 and 4. The generator as above mentioned has an outline to fit within the flanges of the sole plate. The steam generator in the illustration is built up of an assembly of plates of which the bottom plate 26 is preferably of a casting, usually of aluminum which has a series of channels 27. These are indicated as providing a central channel 28, a first divergent channel 29 and a third and outward channel 30 connecting to channel 29 by a neck 31. There are a series of drilled steam escape apertures 32 which align with the steam ducts 15 in the sole plate, these both being drilled at the same time when the generator is assembled in the sole plate to obtain a true registry. The water supply inlet 35 is a casting formed integral with the bottom plate, this fitting in the notch 16 of the flange 13 of the sole plate and extending to one side as shown in Fig. 4 to position the reservoir at one side of the iron. There is a riser end portion 36 and a water duct or passage 37 which leads from the riser which supports a reservoir hereunder described. The discharge of the duct is in the end portion of the center channel 28.

The above mentioned channels for the water supply and the steam generation are spaced apart by a series of ribs indicated by the numeral 40 of which there may be considered a central pair of ribs 41 on each side of the central channel 28, an outer pair of ribs 42 and peripheral ribs 43 at the side meeting at the front or toe of the iron and a rear rib 44. Thus the water channels are in reality formed by depressions between the ribs, the outer or marginal ribs forming a rim. A characteristic of all these ribs and rims is that they have a curved upper surface indicated at 45. This curvature is shown as concave and forms shallow grooves extending lengthwise of each rib. Where the ribs intersect these concave grooves merge together. The water channels are roughened as indicated by the raised portions 46 to obstruct the flow of water and retard the discharge of the steam. There are rivet perforations 47 through the bottom plate 26, these being centered in the ribs and the lower end of each of these perforations is countersunk as illustrated in Fig. 3.

A cap plate 55 is fitted over the bottom plate 26, this conforming to the contour and being sufficiently thin and flexible that it may be depressed in curves such as 56 at the longitudinal grooves 75

of the ribs. This plate is preferably of good heat conducting material as well as being sufficiently thin and soft to be flexible such as being made of a thin sheet of copper. A layer of cement 60 is spread in a plastic form over the cap plate 55. In this a sufficient amount is provided to fill the entire space within the rim 13 of the sole plate and this plastic cement is confined by a top plate 65 which is preferably thicker than the cap plate 55 and considerably stiffer. This plate should have good heat conducting characteristics for which I find aluminum is satisfactory. When assembled the rivet perforations are preferably drilled through the assembly of the plates and plastic, these conforming to alignment with the perforations 47 in the bottom plate. The rivets are then inserted and riveted, the rivets being indicated by the numeral 66 having an upper head 67 pressed into the aluminum top plate and a countersunk bottom head 68 fitting in the countersink of the rivet perforations 47. The pressing of the plates together exerts sufficient pressure on the cap plate 55 which together with the riveting causes this plate to have a concave curvature 56 to conform to the concave grooves 45 on the ribs and the peripheral rib structure. In addition the plastic causes a downward curved depression 69 at the channels of the bottom plate. This with the roughened portions further restricts the cross sectional areas of these channels to the flow of water and steam. The curvatures and the small free areas of the cap plate 55 and of the top plate 65 take care of expansion and contraction of the metals of these plates due to changing temperatures. The cement filling or ceramic between the plates has substantially the same coefficient of expansion as the metal plates confining this cement. No objectionable strains are brought on the thin metal sheets which might otherwise tend to crack these. The whole assemblage forming the steam generator it will thus be seen is the plate structure riveted together with the cement layer forming water and steam tight joints at the edges on the upper surface of the ribs which define the water and steam channels and also at the rivets. This is a unitary structure which may be handled and inserted as desired.

The electric heating unit indicated at 75 is preferably made up of a unitary construction with metal coverings. The heat generator conforms to the shape of the iron having a snug fit inside of the rim 13 of the sole plate of the iron and has a close fit on the top plate of the steam generator.

The assembly of the steam generator and the electric heat generator 75 are confined by a cap plate 80, this preferably being aluminum, shaped at its edges to fit inside of the rim 13 of the sole plate and having diagonal perforations 81 spaced around the rim with countersunk portions 82 to receive screw bolts 83 which attach the cap plate to the sole plate and exert a downward pressure. The cap plate has a center opening 84 to align with an opening in the electric generator to accommodate a thermostat or the like and thermostat control. The iron is completed by providing a weight 90 usually of cast iron, this being secured to the cap plate by countersunk screws 91. A cover hood 95 is formed of pressed metal and is attached to the weight by a screw 96, the handle being attached in a conventional manner. The water reservoir and the water supply system is as hereunder described.

The feature of my invention dealing with the resilient expansible pressure chamber for the supply water is illustrated particularly in Fig. 5 in which the pressure chamber assembly is designated by the numeral 120. For this purpose the water supply inlet 35 as above mentioned has a duct 37 leading to the center channel 28 of the steam generator in the construction of Figs. 3 and 4. For convenience sake and to place the reservoir to one side in order not to interfere with the user of the iron presuming such user is right handed, a water supply inlet extends along the rear end of the iron. Attached to the riser 36 is a screw threaded reservoir support 121 with a reservoir 122 mounted thereon. This is illustrated as having a base 123, sides 124, a top 125 with a filler cap 126. A water discharge elbow 130 is connected to the support or fitting 121 and has a rubber tube 131 attached thereto by a suitable clamp. A nipple 132 is secured to the other end of the rubber tube by another clamp and a ball check valve assembly 133 fitted on the nipple. If desired this may be attached directly to the end of the rubber tube. The inlet for the valve is indicated at 134.

The operation of this expansible chamber structure is as follows: When the iron is being used in pressing garments, water is fed at a suitable rate through the check valve and the various ducts to the channels where the water is boiled to generate steam and the steam discharged. The action of steam generation however is so rapid that sometimes there is a back pressure of steam tending to force the water back into the reservoir. This back flow or back pressure causes a seating of the check valve preventing the back flow of the water. The water trapped in the rubber tube 131 causes an expansion of such tube until such times as the steam pressure decreases, then the contracting action of the resilient pressure chamber causes a flow of water again into the steam generator from the rubber tube before the check valve opens, then as the steam is developed water flows through the check valve into the steam generator. Suitable control valves may be used to regulate the flow of water or the cap may have small registering apertures for inlet of air into the reservoir which will cause a regulation of the flow of water to the steam generator.

In Fig. 6 I illustrate a suitable construction for connection to an overhead reservoir or to a water supply line. In this case the water supply inlet 35 having a riser 36 is provided with a valve 140 which is manually operable. This valve leads to a small section of hose which is expansible and on the top of which there is mounted a check valve 142. An outer jacket connects valve 140 with a needle valve 143 which in turn is connected to a hose 144 that leads to an overhead reservoir or to a water supply line. The electric socket 145 with the lead cord 146 leads off to one side of the iron. When made for a right-hand person this leaves the iron quite free of any obstructions of the electric lead cord or the water hose. The iron may be made in either right or left-hand constructions. The hose on which check valve 142 is mounted functions very much the same as hose 131. The needle valve 143 may be adjusted to cause a correct amount of steam to be generated. Valve 140 permits the feed of water to be turned off or on without disturbing the adjustment of the needle valve.

It is believed unnecessary to enter into a detailed description of the manner of manufacture

of the steam generator 25 shown in sectional detail in Figs. 3 and 4. However, I find it an advantage after spreading the layer of cement 60 over the cap plate 55 which contacts the ribs 5 of the bottom plate 26 while the cement is still sufficiently plastic to flow, to fit the top plate 65 and to so clamp this at the edges that the edges of this plate are bent downwardly whereby, when pressure is exerted forcing the bottom plate 26 and the top plate 65 towards each other, no cement can escape at the peripheral edge of the generator. The steam generator is generally clamped in the process of manufacture between two plates or flat surfaces having openings to permit insertion of a tool to head the rivets. The compression caused by the cement forces the cap plate 55 where it fits over the ribs to conform to the transverse curved shape of such ribs as the cement is confined at its peripheral edge and while still plastic it develops a pressure similar to fluids making a close bond with the rivets. The rivets at the peripheral edge are preferably headed up first and then the rivets through the interior ribs are headed. Of course when the cement sets it no longer acts as a plastic and there is no danger of any escape at the peripheral edge of the steam generator.

Various changes may be made in the details of the construction without departing from the spirit or scope of the invention as defined by the appended claims.

I claim:

1. A steam generator for an electric iron having a bottom plate with a series of connected channels, there being perforations connected with one or more channels for the discharge of steam through the bottom plate, the bottom plate having a series of ribs between channels, a cap plate fitted over the ribs, a hardenable plastic ceramic on the cap plate, a top plate confining the layer of ceramic, rivets extending through the bottom plate, the cap plate, the top plate and the cement and forming water tight joints, there being an inlet for water to at least one of the channels.
2. In an iron, a steam generating unit having a bottom plate with perforations for discharge of steam, a cap plate mounted thereon, there being channels for water and steam between the bottom and the cap plate, a layer of hardenable plastic ceramic on the cap plate, a heat transference top plate, rivets securing the bottom, the cap and the top plate together and forming a steam and water tight connection with the bottom plate and a heat supply unit placed on the top plate.
3. In an iron the combination of a sole plate having an ironing surface and a peripheral flange, a steam generating unit having a bottom plate with a series of connected channels with ribs therebetween, the ribs having a curved upper surface considered transversely, a cap plate fitted over the ribs and shaped to the contour thereof, a layer of hardenable ceramic on the cap plate, a top plate confining the ceramic, rivets extending through the ribs of the bottom plate, the cap and top plates, there being a water connection to one of the channels and steam discharge perforations through the sole plate and the bottom plate and an electric heating unit on the top plate and a securing means engaging the heating unit and the said flanges.
4. A steam generator for irons including a flat surfaced bottom plate having a series of connected channels spaced apart by ribs, the ribs

having a curved upper surface considered transversely to each rib, a cap plate on the ribs and shaped to conform to the curved shape of the tops of the ribs, the cap plate with the bottom plate and the channels forming a series of passages for water and steam, a layer of hardenable ceramic on the cap plate, a flat top plate resting on and confining the cement, rivets extending through the bottom, the cap and the top plates at the ribs and forming water and steam tight joints, the bottom plate having discharge perforations for steam and a water inlet connection to one of the channels.

5. In an electric iron a steam generator having passages for water and steam, a water supply reservoir, a connection from the reservoir to one of the passages having an intake check valve and a resilient expansion chamber located on the opposite side of the check valve from the reservoir expanding under the action of water forced back against the check valve by the generation of steam and adapted by its resiliency to feed water to the said water and steam passages prior to the opening of the check valve.

6. In a steam generating iron having passages for water and steam and the discharge of steam, a water supply connection to one of the passages including a check valve and a tubular expanding structure between the check valve and the passages, the expanding structure being adapted to expand under the action of water forced backwardly against the closed check valve and on contraction to feed water to the passages prior to the opening of the check valve.

7. In an iron for generating steam from water and discharging the steam, the combination of a water supply connection having a check valve closing on the back flow of water or steam, an expansible rubber tube between the check valve and the steam generator, the said tube being adapted to expand when filled with water forced

against the closed check valve by pressure of steam and on release of the steam pressure to feed water prior to the opening of the check valve.

5. A steam generator for electric irons comprising a bottom plate having connected channels on its upper surface, holes for the discharge of steam in the bottom plate at the bottoms of at least some of said channels, a deformable plate disposed over the tops of the channels, a hardenable plastic ceramic over the deformable plate, a cap plate over the plastic, and means for securing the cap plate and bottom plate together.

9. A steam generator for electric irons comprising a bottom plate having connected channels defined by ribs on its upper surface, holes for the discharge of steam in the bottom plate at the bottoms of at least some of said channels, a deformable plate disposed over the tops of the channels, a hardenable ceramic over the deformable plate, a cap plate over the ceramic, and means for securing the cap plate and bottom plate together through the ribs defining said channels.

20 10. A steam generator for irons comprising a bottom plate having upstanding ribs defining a plurality of connected channels, the top surfaces of the ribs being concave, a deformable plate resting on the ribs, ceramic material over the deformable plate, a cap plate over the ceramic material, and means connecting the cap plate and bottom plate together.

25 11. A steam generator for irons comprising a bottom plate having upstanding ribs defining a plurality of connected channels, the top surfaces of the ribs being concave, a deformable plate resting on the ribs, ceramic material over the deformable plate, a cap plate over the ceramic material, and means connecting the cap plate and bottom plate together through said ribs.

MORRIS A. SCHWARTZ.
